UNITED STATES PATENT OFFICE

EVENCE COPPÉE, OF BRUSSELS, BELGIUM

COKE OVEN

Application filed June 15, 1928, Serial No. 118,085, and in Belgium June 22, 1925.

The present invention relates to a re-generating coke oven and relates more particularly to the method of circulation of the gases in the pillars or walls containing vertical flues in such a way as to produce a more advantageous exchange of heat between the burning gases and the charge to be coked.

The object of the present invention is to increase the speed of the gaseous current with a view to increasing the transmission of heat by convection which, for an equal amount of sensible heat carried along, produces a greater exchange of heat through the heating wall, and obtaining an increased production on account of the possibility of supplying a greater quantity of combustible gases.

For this purpose, according to the invention, the vertical wall of the coke oven is formed of an even number of groups of vertical flues each of which is connected to the one adjacent to it by a connecting chamber, these chambers being arranged alternately at the top and at the bottom along the length of the wall; the whole of the fluid burning agent is admitted into the first group with a fraction of the total amount of gas serving for the combustion while the other parts of the gas are admitted along the path of the burning current of gas where they encounter a greatly diluted agent which produces a slow burning with a long flame.

The fraction of the combustible gases is admitted at the base of the uptake flues of the outer group through a duct the reduced length of which obviates any cause of formation of graphite which results when this duct extends into the central and hottest part of the oven and from the prolonged stay of the gas the speed of which decreases with the amount of its distribution.

A coke oven according to the invention also renders the coking temperature uniform over the whole length of the vertical wall and obviates the disadvantages of having a lack of homogeneity in the quality of the coke on account of the unequal burning or baking in the different parts of the oven.

In order to obviate a rapid baking in the neighborhood of the point of ignition of the

gas and the production, at the base of the coke cake, of a dead baked coke of reduced burning power, certain constructors have provided for the carbonizing chamber to decrease in width upwardly in proportion to the fall in temperature of the gases as they ascend.

This solution, which is favorable in the case of the uptake flues, nevertheless increases the effect in the case of the downtime flues where the temperature of the gases continues to decrease while the thickness of the layers to be coked increases.

On the contrary in the oven according to the present invention, in which the fluids of the combustion, reassembled into one single current pass through the heating flues with a much greater volume, the drops in temperature of these fluids, for an equal amount of heat given up, decrease on account of the magnitude of their volume and the thermal potential remains practically constant over the whole height of the oven, whether the flow is up or down.

Other features and advantages of the oven according to the invention will appear from the description hereinafter given, by way of example, of a coke oven constructed according to the invention and illustrated in the accompanying drawing, in which:

Figure 1 is a longitudinal section through the vertical walls showing the arrangement of the various groups of flues as well as the intakes for the gas serving for combustion.

Figure 2 is a sectional elevation taken along the line II—II in Figure 1.

Figure 3 is a sectional elevation taken along the line III—III in Figure 1.

As shown in the drawing, the vertical wall of the coke oven is formed by an even number of groups of vertical flues 3 each group being separated from the one adjacent to it by a partition dividing wall. These flues may be of any number and the number may vary from one group to the other.

Each group communicates with the adjacent group to the right or the left of it by a communication chamber 2 the position of which is such that over the whole length of the vertical wall the chambers 2 are alter-

nately at the upper and lower ends of the flues. The current of burning gas therefore follows an undulating or sinuous path, each group of flues being traversed by a strong current of gas evolved and the direction of flow of these gases being alternated from one group to the one adjacent to it.

In Figure 1 it has been assumed that in the stage of regeneration considered the current flows from left to right.

The air supplied for the combustion is re-heated in the regenerator 4 and is distributed by ducts 5 disposed at the base of the uptake flues of the outer group according to the draught regulated by the dampers or slides 14 disposed at the upper part of the flues (Fig. 2). A part of the gases serving for the combustion, called primary gas, is forced through the pipe 6 into the distributing duct 7 and is distributed into the same flues 3 by means of calibrated and removable nozzles 9 to which access is obtained through the inspection holes 10 provided in the roof of the vertical wall.

The gaseous current ascending through the flues 3 forming the outer group referred to is then reversed in direction in the following group in such a way as to produce a baffled flow passing successively through the whole of the flues of each group. Near the points of reversal situated at the upper part of the vertical flues are provided secondary gas inlets 11, 12, and 13 in order to compensate for the heat given up in each of the preceding groups and to maintain in the following divisions a burning with a long flame obtained by the degree of dilution of the fluid burning agent in the inert mass of burnt gases produced by the previous burnings. Dampers or slides 15 similar to the slides 14 ensure the equal distribution of the gaseous current in the vertical flues forming the successive groups.

The arrangement of the duct 7 of small length serving for the distribution of the primary gas at the base of the uptake flues of the outer group only, obviates any cause tending to the formation of graphite.

This graphite is formed particularly when the primary gas inlet duct is arranged in the central part of the oven and as a consequence of a prolonged stay of these gases in these ducts.

The oven is therefore adapted for the use of fuels of most differing natures, from water gas of relatively low calorific value to gases which are most rich in hydrocarbons, such as coke oven gas dehydrogenated in the manufacture of synthetic ammonia which is difficult to employ on account of its aptitude for forming graphite deposits in the ducts which take part in its distribution.

The coke oven thus constructed presents the advantages that a very regular coking in the different parts of the oven and a better

transmission of sensible heat towards the charge under treatment are obtained while at the same time enabling the productive capacity of the oven to be increased, the dimensions of the coking chamber of which oven may be made considerably greater by increasing at the same time the admission of air and gas in a proportion which is not permissible in systems in current use on account of the pyrometric resistance of the materials employed. It is in fact observed that the control of the heating is not only associated to the temperature of combustion which depends upon the amount of sensible heat supplied and the calorific value of the fuel employed but that as the transmission of heat is limited to the value of the thermal potential between the opposite faces of the heating wall, the heating action will be as much greater as the supply of calorific energy, per unit of time, is greater. It follows that in ovens of the present day type in which for reasons of economy it is convenient to regulate the burning with the greatest precision, that is to say with a minimum amount of excess air, it is impossible to greatly increase the normal supply of gas and air without reaching a temperature which is dangerous to the preservation of the refractory brickwork.

In the oven according to the present invention the total amount of air is admitted into the outer group, with which air is incorporated only a part of the gas, which enables a lower temperature of combustion to be obtained and consequently a greater calorific energy to be supplied to the coking operation, by means of a greater admission of gas and air, without exceeding the limiting working temperature obtaining in other oven systems. The secondary admissions of gas, the object of which is to compensate for the falls in temperature in the various parts of the oven will also increase with the magnitude of this current and will co-operate in order to supply to the heating a maximum calorific energy of which use is made on account of the greater power of transmission which is due to the speed of the gaseous current in the vertical wall. These secondary admissions of gas are made from the top of the oven into the gases resulting from a previous burning and as a consequence of a relatively low burning power which gives the flame the additional length necessitated by the extension of the paths in ovens of large dimensions.

This retarding of the combustion is employed to advantage, in the direction of progression of the flame, from the upper end of the first group where the gaseous current receives the first admission of secondary gas so as to give the flame of the primary gas simply an ascending circulation of length half as much as the successively ascending and descending flow of the flame in other oven systems.

It follows from these various points that, in the oven according to the present invention the height of the charge may be increased beyond the allowable limits in the ordinary coking process and that the advantages obtained—the increased power of transmission, the possibility of supplying more calorific energy and further lengthening the flame—increase the productive capacity to a considerable extent.

10 What I claim is:

In a coke oven, a coking chamber, a heating wall for said chamber comprising a series of an even number of at least four groups of vertical combustion flues, said groups being communicatively connected together in series by horizontal bus flues above, and at least one horizontal bus flue below, said vertical combustion flues, means for admitting air into and discharging burnt gas alternately from, each of the outer groups, means for admitting fuel gas into each of the outer groups, and means for admitting fuel gas directly into each of the upper bus flues.

20 In testimony whereof I affix my signature.
